Primary Examiner — Ian Simmons*Assistant Examiner* — Keith Frank*(74) Attorney, Agent, or Firm* — Norton Rose Fulbright US LLP(57) CLAIM

The ornamental design for a food container, as shown and described.

DESCRIPTION

FIG. 1 is a front perspective view of a food container showing our new design;
FIG. 2 is a front elevation view thereof;
FIG. 3 is a back elevation view thereof;
FIG. 4 is a right elevation view thereof;
FIG. 5 is a left elevation view thereof;
FIG. 6 is a top plan view thereof; and,
FIG. 7 is a bottom plan view thereof.

The broken lines shown in the figures represent unclaimed subject matter and form no part of the claimed design.

1 Claim, 5 Drawing Sheets(56)
